CLAIM

The ornamental design for a battery as shown and described.

DESCRIPTION

FIG. 1 is a front, left, and top perspective view of a battery in accordance with my new design;

FIG. 2 is a front elevational view of the battery in accordance with my new design;

FIG. 3 is a rear elevational view of the battery in accordance with my new design;

FIG. 4 is a left side elevational view of the battery in accordance with my new design;

FIG. 5 is a right side elevational view of the battery in accordance with my new design;

FIG. 6 is a top plan view of the battery in accordance with my new design; and,

FIG. 7 is a bottom plan view of the battery in accordance with my new design.

The lighter grey portions are for the purpose of illustrating unclaimed portions of the battery that form no part of the claimed design. The broken line indicates the boundary of the claimed design and forms no part of the claimed design.

1 Claim, 7 Drawing Sheets
